UNITED STATES PATENT OFFICE.

WEBSTER F. TRAVES, OF CLEVELAND, OHIO, ASSIGNOR TO THE BROWN HOISTING MACHINERY COMPANY, OF CLEVELAND, OHIO, A CORPORATION OF DELAWARE.

DEVICE FOR UNLOADING CARS.

SPECIFICATION forming part of Letters Patent No. 768,006, dated August 16, 1904.

Application filed January 24, 1903. Serial No. 140,404. (No model.)

To all whom it may concern:

Be it known that I, WEBSTER F. TRAVES, a citizen of the United States, and a resident of Cleveland, county of Cuyahoga, and State of Ohio, have invented a new and useful Improvement in Devices for Unloading Cars, of which the following is a specification, the principle of the invention being herein explained and the best mode in which I have contemplated applying that principle so as to distinguish it from other inventions.

My invention relates to devices for unloading cars, and is particularly adapted for use in unloading grain from what is known as "box-cars."

The invention has for its object the unloading of cars in a quick, economical, and efficient manner; and it consists of means hereinafter fully described, and particularly set forth in the claims.

The annexed drawings and the following description set forth in detail certain mechanism embodying the invention, such disclosed means constituting but one of various mechanical forms in which the principle of the invention may be used.

In said annexed drawings, Figure I represents a side elevation of an unloading device embodying my invention as applied to grain unloading and showing a box-car secured thereon and ready for the operation of unloading. Fig. II represents an end elevation of said device and car with certain parts omitted. Fig. III represents an elevation of that portion of the device omitted from Fig. II, showing a part of the remainder and a car in dotted lines to indicate the relationship of such parts. Fig. IV represents a plan view of the parts shown in Fig. III, together with related parts and a car in dotted lines. Fig. V represents a side elevation of a structure embodying my said invention, showing a series of grain-bins, a rail-bed and track, and an approach trestle and track for conducting cars to the said structure.

A base-truck A is provided with traction-wheels α , running upon a track B, which flanks a series of grain-bins C. Upon the truck is

mounted an engine A', which operates one set of traction-wheels through suitable gearing, 50 as shown in Fig. II, such arrangement being but one of various well-known arrangements for effecting the traction of a structure along a track. This engine is controlled from a convenient point in the structure, as will be readily understood. Secured to this truck are two upright standards D D, provided at the top with bearings d^1 d^2 for two trunnions e e , secured to and forming a transverse oscillatory axis for a frame E. To the under surface of 60 this frame are secured two large gear-segments E' E', Figs. I and II. Mounted upon the lower portion of the standards D are two transverse shafts d d , each carrying two pinions d' d' , which mesh with the segments E'. 65 These shafts are each provided at one end with a bevel-gear d^2 , engaged on similar sides by a bevel-pinion d^3 , so as to be capable of rotation in the same direction. These pinions are mounted upon a crank-shaft d^4 , rotated by a 70 reversible double-cylinder engine D'. Suitable cross-bracing is provided for properly strengthening the segments, and intermediately of the segments and standards are mounted a number of friction-rollers d^5 to prevent 75 any lateral movement of the segments. It is thus seen that the frame may be oscillated in longitudinal planes about its oscillatory axis.

Upon the upper portion of the frame E are a series of transverse bearing-surface plates e' , having their central portion grooved and formed with rack-teeth. Each end of each such bearing-surface is provided with a fixed stop e'' . Upon the surfaces of these plates are mounted a series of rockers F, braced and connected to form a cradle, each formed with gear-teeth f and curved bearing-surfaces f' on each side of same. The bearing-surfaces f' rest upon the bearing-surfaces of plates e' , and the teeth of the latter engage the gear-teeth f . 85 Upon the upper portion of these rockers are secured the rails of a longitudinal track F' of standard gage for receiving a car G. The track and cradles are suitably braced, so as to form a strong structure, serving as a wheel-base for the car. This wheel-base, it will be 90 95

seen, may be caused to rock or oscillate upon the rockers and in transverse planes, such rocking movement being limited by the stops c^2 , whereby it may, by reason of the oscillatory construction of frame E, which supports it, be tilted both longitudinally and laterally, at the same time, as indicated by the dotted lines in Figs. I and II.

Upon one leg of one of the standards D is secured a hanger H, in which is slidably mounted a bolt h, which is adapted to engage the space between any two of the teeth of the adjacent segment E'. This bolt is operated to so engage said segments or to disengage same by means of a lever h', suitably connected therewith. By means of this bolt it is seen that the frame E may be locked in a various number of angular positions or locked in a horizontal position, as shown.

Projecting from each side of the wheel-base is a beam F³, to each of which is secured the end of a cable f², which passes down and is secured to a drum F³, operated by an engine F⁴.

At each end of the wheel-base and in the central portion thereof is pivoted a post F⁵, which may be raised into the path of the car, caused to contact the ends of the latter, and so prevent longitudinal displacement thereof after the device is tilted. These posts are operated to perform such function by cables f⁴ attached thereto, running over suitably-located idle pulleys and attached to a drum f⁵. This drum is operated by a suitable engine F⁶.

Near each end and upon opposite sides of the track on the wheel-base are secured four upright rigid posts F⁷ F⁸. Each post is provided with a screw-shaft f⁶, operated by a hand-wheel f⁷ and adapted at its inner end to contact the adjacent side of the car and clamp the latter, so as to secure same against lateral displacement when the device is tilted.

Upon the lower side of the wheel-base are secured two beams k k, which extend laterally therefrom, as shown in Figs. III and IV. Upon the ends of these beams is secured a frame K, consisting of cross-pieces k' k', angularly-mounted upright posts k¹ k², and cross-braces k³ k⁴. These posts are provided with a runway for a longitudinally-slidable bar K', provided upon its upper surface with a rack k⁴. This rack is engaged by a pinion k⁵, secured to a crank-shaft k⁶, mounted in suitable bearings in the frame. At the inner end of said bar is secured a flat diaphragm K², of wood, having the same angularity as has the bar K'. This angularity is made substantially equal to that of a line drawn from one end of one door in a box-car to the opposite end of the other door of such car. Such diaphragm is given a height from the wheel-base substantially such that its lower end shall be in the same plane with the bottom of the car, sufficient clearance being allowed to permit the diaphragm to be readily moved. It is thus seen that the diaphragm may be inserted in the car through

one door and caused to divide its interior into two trapezoidal compartments, each of which is in communication with one door and cut off from such communication with the other, as shown in Fig. IV.

The engines above mentioned may be operated by compressed air supplied from some suitable source through properly located and arranged ducts, or they may be operated by steam generated in a boiler L, located upon the truck A, as shown in Fig. V, and suitably connected therewith, all of which will be readily understood by those skilled in the art.

In operating the above-described device the structure is first moved up to the trestle, as shown in said Fig. V, so as to cause the track F' to abut the trestle-track. The car to be unloaded is now moved up the trestle onto the track F', whereupon the posts F⁵ are raised so as to contact the car's ends, and so prevent longitudinal movement thereof on said track. The screws f⁶ are then caused to secure the car laterally, as shown in Fig. II. The structure is now transported along track B to the point of unloading, so as to bring the car-door opposite a suitable hopper provided at such point and shown in dotted lines in said Fig. II. Engine D' is now operated to tilt the frame E and wheel-base longitudinally toward the right, as shown in dotted lines, Fig. I. The frame and base are then locked in this position by means of bolt h. Engine F⁴ is now operated to tilt the wheel-base laterally toward the chute. The car-door is now opened sufficiently to admit the diaphragm K², which is shoved into the car and assumes the position shown in Fig. IV. Upon opening the door wide the contents of the upper half of the car are discharged, the diaphragm diverting such contents through the limited area represented by the door. In order to discharge the contents of the other side, the car is tilted in the opposite direction and the opposite door opened, a suitable hopper being provided for receiving same.

If it is desired to unload the entire contents on the same side of the track, a second diaphragm may be provided, mounted and constructed in a manner similar to that described, but located upon the other side of the door and having the opposite inclination, as will be readily seen. A diaphragm construction may also be provided in which a single diaphragm may be given the opposite inclinations.

Any suitable means for retracting the oscillatory posts F⁵ may be used. I have shown for this purpose a rope F⁸, secured thereto, passing over a suitable pulley mounted at a convenient point, and a weight F⁹, secured to the rope's end.

Other modes of applying the principle of my invention may be employed instead of the one explained, change being made as regards the mechanism herein disclosed, provided the means stated by any one of the fol-

lowing claims or the equivalent of such stated means be employed.

I therefore particularly point out and distinctly claim as my invention—

- 5 1. The combination with a car-carrier mounted so as to be capable of tilting a car, of means separate from the car for diverting the contents of the car out of the latter, while the car is on such carrier, toward a given 65 opening in the walls of the car.
2. The combination with a car-carrier mounted so as to be capable of tilting a car, of means movable into and removable from the interior of a car while on such carrier, for 70 diverting the contents thereof out of same toward a given opening in the car.
3. The combination with a car-carrier mounted so as to be capable of tilting a car, of means inclined relatively to the direction of 75 tilting, arranged to divert the car's contents, while such car is on said carrier, toward a given area within its interior.
4. The combination with a car-carrier mounted so as to be capable of tilting a car, of means within a car and separate from the 80 ranged to divert the car's contents out of the same, while the latter is on such carrier, arranging a car toward a given opening in its walls.
5. The combination with a car-carrier mounted so as to be capable of tilting a car, of means mounted upon such carrier inclined relatively to the direction of such tilting and arranged to divert the contents of a car while 85 the latter is on such carrier and in a tilted position.
6. The combination with a car-carrier mounted so as to be capable of tilting a car, of means mounted upon such carrier inclined relatively to the direction of such tilting and 90 arranged to divert the contents of a car while the latter is on such carrier and in a tilted position, such diverting means being movable into and out of the car.
7. The combination with a car-carrier having two planes of oscillatory movement angularly related to each other, of means for diverting the car's contents toward a given area 95 in the side of such car.
8. The combination with a car-carrier having two planes of oscillatory movement angularly related to each other, of means mounted upon such carrier for diverting the car's contents toward a given area in the side of such car.
- 55 9. The combination with a car-carrier having two planes of oscillatory movement angularly related to each other, of a diaphragm mounted upon such carrier for diverting the car's contents toward a given area in the side 100 of such car.
- 60 10. The combination with a car-carrier having two planes of oscillatory movement angularly related to each other, of means for diverting the car's contents toward a given area

in the side of such car, such means being arranged to be secured in an angular position in the car's interior.

11. The combination with a car-carrier having two planes of oscillatory movement angularly related relatively to each other, of a diaphragm mounted upon such carrier, and arranged to be inserted in the car so as to assume an angular position across the latter.

12. The combination with a support having an oscillatory movement and arranged to receive a car, of means separate from such car for diverting the contents of the latter toward a given opening in the car-walls and out of the car.

13. The combination with a support having an oscillatory movement and arranged to receive a car, of a diaphragm extending transversely of its interior.

14. The combination with a support having an oscillatory movement and arranged to receive a car, of a diaphragm extending upwardly from the floor and across such car.

15. The combination with a support having an oscillatory movement and arranged to receive a car, of a diaphragm extending across the car's interior in an inclined direction relatively to such car.

16. The combination with a support arranged to tilt a car, of a diaphragm movable into and out of such car.

17. The combination with a support arranged to tilt a car, of a diaphragm mounted so as to be movable transversely of such support.

18. The combination with a support arranged to tilt a car, of a diaphragm mounted so as to be movable transversely of such support and in a direction inclined relatively thereto.

19. The combination with a wheel-base having a lateral oscillatory movement, of a diaphragm mounted upon such base and movable transversely of same.

20. The combination with a wheel-base having an oscillatory movement, of a diaphragm mounted upon such base, movable transversely of same and arranged to assume an inclined position over said base.

21. The combination with a wheel-base having an oscillatory movement, of a diaphragm angularly mounted upon such base and arranged to be movable longitudinally of itself.

22. The combination of a wheel-base having an oscillatory movement, a frame secured to such base, a movable bar mounted upon such frame in a position angular relatively to said wheel-base, a diaphragm secured to the end of said bar at a height such as to be capable of insertion into a car-door.

23. The combination of a wheel-base oscillatorily mounted, a support for such base oscillatorily mounted and means separate from a car for diverting the latter's contents toward

a given opening in the said car and out of the latter.

24. The combination of a wheel-base oscillatorily mounted, a support for such base oscillatorily mounted, and means supported by said wheel-base arranged to be moved into and out of a car on such base and adapted to divert its contents.

25. The combination of a wheel-base oscillatorily mounted, a support for such base oscillatorily mounted and a diaphragm supported by such base and arranged to be moved into and out of a car on such base.

26. The combination of a wheel-base oscillatorily mounted, a support for such base oscillatorily mounted, and a diaphragm supported by such base and arranged to be moved into and out of a car on such base and to assume a position therein inclined relatively to the car.

27. In means for unloading cars, a carrier comprising the combination of a base, an oscillatory frame mounted upon said base and provided with transverse bearing-surfaces and

25 a cradle provided with a series of curved rock-

ers resting upon said transverse bearing-surfaces.

28. In means for unloading cars, a carrier comprising the combination of a base, an oscillatory frame mounted upon said base and provided with transverse bearing-surfaces, a cradle provided with a series of curved rockers resting upon said transverse bearing-surfaces, and means for securing a car upon said cradle against longitudinal and transverse displacement.

29. In means for unloading cars, a carrier comprising the combination of a base, a frame mounted upon trunnions supported upon said base, two gear-segments secured to said frame, 40 pinions engaging said segments and mounted upon said frame and a bolt mounted upon the latter for engaging one of said segments to lock same.

Signed by me this 17th day of January, 45
1903.

WEBSTER F. TRAVES.
